By his Attorney # UNITED STATES PATENT OFFICE.

JAMES F. HILL, OF FLEETWOOD, PENNSYLVANIA.

FIRE-ESCAPE.

SPECIFICATION forming part of Letters Patent No. 462,866, dated November 10, 1891.

Application filed February 24, 1891. Serial No. 382,415. (No model.)

To all whom it may concern:

Be it known that I, JAMES F. HILL, a citizen of the United States, residing at Fleetwood, in the county of Berks, State of Pennsylvania, have invented certain Improvements in Fire-Escapes, of which the following is a specification.

This invention relates to an improved mechanism adapted more especially for supporting 10 the rope or ladder of a suspended fire-escape.

The objects are to provide a bracket or support which may, first, be secured in such a manner as to insure absolute safety; second, which may be swung out of a window, ready 15 for immediate use, or swung in and dropped out of the way; third, which will be adjustable to suit different windows. The means by which I accomplish these objects are fully described in connection with the accompanying 20 drawings, and the invention involved is specifically pointed out in the claims.

Figure 1 is a sectional elevation of a portion of the wall of a building, showing my improved bracket swung outward, ready for 25 use. Fig. 2 is a corresponding inside view showing the bracket swung into the room and dropped to its normal position between the floor and the window-sill. Fig. 3 gives another view of the shoe attached to the supporting 30 leg.

A represents a window-frame, a the outside window-sill, and K the floor.

H is a casing containing pulleys and friction devices to be used in connection with a 35 rope h—such a construction, for instance, as is described in my patent, No. 432,045, issued July 15, 1890. This is fastened to one end of an iron bar b, the opposite end of which is adjustably secured to an extension-bar B, a series of holes b² being provided in each to permit the lengthening or shortening of the arm or bracket formed by them jointly. The inner end of this arm B is pivoted at b³ to an eye on the top end of a vertical rod E, which 40 is guided by a small bracket f, secured to the inner edge of the window-sill and adjustably secured by nuts e to a bracket F, fastened securely to the floor-joists. The leg C is secured intermediately to the arm B by means of 45 bolts passing through one of the holes c', the

arm being braced by a bar D, also adjustably secured to the arm at a point near its outer end and to the lower portion of the leg C. The end of the latter is provided with a shoe G, pivoted thereto by means of a lug g, so as 55 to permit it to swing downward, as shown in Figs. 2 and 3, yet providing a broad surface to support the strain brought upon it when in operative position upon the window-sill, as shown in Fig. 1.

In applying my bracket as above described it is only necessary to change the relative lengths of the arm B, leg C, and brace D to adapt it to varying shapes of windows and sills and to secure any desired angle for the 60 arm B. When properly arranged and placed in the position indicated in Fig. 1, the principal strains developed by a weight suspended from the rope h are a tensile strain on the rod E, which is conveyed through the nut e 70 and bracket F to the floor, and a compression conveyed from the leg C, through the shoe G, to the sill a. When not in use, the position of the apparatus is as shown in Fig. 2. To change from one position to the other it is 75 only necessary to lift the arm B on its pivotal connection b³ until sufficiently high to allow it to pass readily through the window-opening, which is effected by a swinging movement, the vertical rod E turning in the bearings F f. It is then lowered to either of the 80 positions shown, the shoe G dropping to the vertical position, as in Fig. 3, to avoid its projecting into the room, but taking the horizontal position, as in Fig. 1, when in service.

It is evident that the construction may be made to fixed proportions, instead of being made adjustable, as described, and that it may be otherwise modified. I do not, therefore, limit myself to the exact construction 85 herein set forth; but

What I claim is—

1. In a fire-escape apparatus, the bracket or arm B, provided with the intermediate supporting-leg C and having its inner end pivotally secured substantially as described, whereby it is adapted to be swung in both a vertical and horizontal plane, substantially as 95 set forth.
2. In a fire-escape apparatus, the bracket or 100

arm B, having its inner end pivotally supported, as described, and provided with an intermediate supporting-leg C, having a pivoted foot G, substantially as and for the purpose set forth.

3. In a fire-escape apparatus, the extensible bracket or arm B, having its inner end supported, as at b^3 , and provided with an adjustable leg C and adjustable leg-brace D, substantially as set forth.

4. In a fire-escape apparatus, the bracket or

arm B, provided with the intermediate supporting-leg C, and having its inner end pivoted at b^3 to a vertically-guided rod E, rotatably secured to a fixed support F, substantially as set forth.

In testimony whereof I affix my signature in presence of two witnesses.

JAMES F. HILL.
